FIG. 1 is a front elevational view of a combined air freshener
and picture frame showing my new design;
FIG. 2 is a rear elevational view thereof;
FIG. 3 is a side view, taken from the left side of FIG. 1;
FIG. 4 is a side view, taken from the right side of FIG. 1;
FIG. 5 is a top plan view thereof;
FIG. 6 is a bottom plan view thereof; and,
FIG. 7 is a perspective view thereof, on a reduced scale, the
broken line drawings of a vehicle rear view mirror and the
image on the frame are for illustrative purposes only and
form no part of the claimed design.
